United States Patent Office

Des. 178,629
Patented Sept. 4, 1956

178,629

NOVELTY VENDOR BUILDING

Theodore L. Beach, Jr., New Carlisle, Ohio

Application November 28, 1955, Serial No. 39,069

Term of patent 14 years

(Cl. D52—2)

FIG-1

I claim:

The ornamental design for a novelty vendor building, substantially as shown.
